Inventor:

Germann Herll.

UNITED STATES PATENT OFFICE.

HERMANN HERLT, OF NEW YORK, N. Y.

DESIGN FOR PULLS FOR DOORS, DRAWERS, &c.

Specification forming part of Design No. 5,528, dated February 13, 1872.

Specification describing a Design for an Ornamental Pull, invented by HERMANN HERLT, of the city and county of New York.

The nature of my design is fully represented in the accompanying photographic illustration, to which reference is made.

A represents the head or figure. B represents a handle supported by a rod passing through it, the said rod being held loosely within the mouth of the head. The handle may be constructed of various forms and colors, as desired, to suit the article to which it may be attached.

I am aware that it is not new to make orna-

mental pulls. The distinctive character of my design is found in the head or figure.

I am aware that heads have been frequently used as ornamental pulls, and therefore do not claim broadly such a design; but

What I claim as my invention is—

The design for a pull, consisting of a head and single rod, with its handle depending from the mouth, all as shown in the accompanying illustration.

HERMANN HERLT.
